UNITED STATES PATENT OFFICE.

ADELMER M. BATES, OF CHICAGO, ILLINOIS, ASSIGNOR TO BATES VALVE BAG COMPANY, OF CHICAGO, ILLINOIS, A CORPORATION OF WEST VIRGINIA.

JIGGING DEVICE FOR BAG-FILLING MACHINES.

Application filed June 2, 1922. Serial No. 565,352.

To all whom it may concern:

Be it known that I, ADELMER M. BATES, a citizen of the United States, residing at Chicago, in the county of Cook and State 5 of Illinois, have invented a certain new and useful Improvement in Jigging Devices for Bag-Filling Machines, of which the following is a specification.

This invention relates to a jigging device 10 for bagging machines, and is illustrated more or less diagrammatically in the accompanying drawings wherein:

Figure 1 is a front elevation with parts omitted and parts in section;

15 Figure 2 is a section on line 2—2 of Figure 1;

Figure 3 is a section on line 3—3 of Figure 2;

20 Figure 4 is a section on line 4—4 of Figure 3;

Figure 5 is a detail of the driving mechanism showing the driving pinion and its mounting with parts in section;

25 Figure 6 is a section taken on line 6—6 of Figure 5;

Figure 7 is a plan view on a reduced scale of the mounting of the bearing shown in Figure 5.

30 Like parts are designated by like characters throughout.

The bagging machine is mounted upon a frame provided with end members A, A which are united at their bottoms by a pair of longitudinal members A', A'. Across 35 the top of the machine is a multiple hopper B adapted to receive material to be packed and to empty it into a plurality of feeding means which are located beneath the chest B'. These feeding means are not here 40 shown in detail and will not be described in detail as they form no part of the present invention. They are shown in Figure 2 diagrammatically wherein B² is an impeller casing to which material is fed from the 45 hopper B through the chest B'. It is provided with a shut-off valve B³ operated by the handle B⁴. Extending from the impeller casing B² is a feed nozzle B⁵ which is adapted to be inserted into a bag B⁶ and 50 through which material is fed into the bag.

The feeding means include impellers whereby the charge to be fed into the bag is fed in under power. C is a pulley adapted to be driven by any suitable source of

power and fixed upon a shaft C' which is 55 carried at one end in a bearing C² mounted upon a supporting arm C³ which is connected to one of the end members A. The shaft C' is suitably supported upon other bearings throughout its length. At its 60 other end it is provided with a pair of belt pulleys D, D'. From the pulley D a belt D² furnishes power to a pulley D³ which is fixed upon a driving shaft D⁴. This shaft 65 extends across the back of the machine and carries at its other end a pinion D⁵ which is in mesh with the gear D⁶, which as here shown is covered by a protecting casing D⁷. The gear D⁶ is fixed upon a power shaft D⁸ which lies in the same horizontal plane as 70 the shaft D⁴. From this shaft D⁸ some of the impellers of the feeding mechanism are driven.

Extending from the belt pulley D' is a 75 belt E which drives a pulley E' on a shaft E². Eccentrically connected to this shaft are a plurality of jigging rods E³, each of which carries at its outer end a jigging foot E⁴ which is mounted upon a rocker bar E⁵ which is pivoted at its lower end as at 80 E⁶. By means of the rotation of the pulley E' and the consequent movement of the rods E³ the jigging feet E⁴ jig and pound against the bags B⁶ and thus serve to assist in settling the material as it is fed into them. 85 The pivot E⁷ connecting the rocker bar E⁶ to the jigging foot E⁴ is preferably above the bag contacting surface of the foot, as shown. The longer rocker bar gives the foot a more nearly straight line motion 90 than would a shorter bar pivoted to the foot opposite to or below the bag contacting surface.

Pivoted upon the shaft D⁴ is an arm F. 95 This arm carries at its outer end a weighted roller F' which is adapted to bear upon the belt D² to assist in tightening it. Sometimes when the machine is operating under full load there is a tendency of the belt to slip, and the operator will seize the handle F² at the end of the arm F and depress it to tighten the belt. Upon his releasing the handle there is a tendency of the arm to be thrown violently upward, sometimes resulting in injury to the operator or to the machine. To prevent this a lateral extension F³ is provided on the chest B' and a pivotal spring held member F⁴ is mounted in the 100 105

handle F². This member is normally held in position shown in full lines in Figures 1 and 3 by means of the helical spring F³. When the parts are in this position, if the 5 arm F is thrown upward, its movement is limited and it cannot damage either the operator or the machine. When it is necessary to raise the arm above this limited position the part F⁴ is depressed against the 10 spring F⁵ and it then clears the extension F² and the arm may be moved upward.

Figures 5, 6, and 7 illustrate in detail the arrangement and mounting of the pinion D⁶. The pinion is carried in a bearing G which 15 is mounted upon the bracket G' which extends laterally from the chest B'. At its upper end the bracket G' is provided with a surface G² which has in it a pair of slots G³, G⁴ and an enlarged central opening G⁴.

20 When the bearing G is mounted on the surface G² it is moved so that the heads G⁵ of the attaching bolts G⁶ come one of them into the enlarged opening G⁴ and the other one entirely outside of the system of slots. 25 The bearing is then moved laterally so that the shanks of the bolts come into the slots G³ and the heads are thus in engagement with the lower surface and the nuts are tightened and the bearing held in position.

30 The bag B⁶ to be filled is supported in an A-frame H. Each is pivotally mounted at its upper end upon a bar H'. This bar is itself pivotally mounted at H². The details of this second pivotal mounting will not 35 here be described as they form no part of the present invention. At their lower ends the sides of the A-frame H are forked as at H³ and rest upon the ends of a pair of scale beams, the details of which will not be fully 40 described as they form no part of the present invention. Connected to the main A-frame side members H are a pair of downward extensions H⁴ which are joined together at the bottom preferably by a plate H⁵. Mounted 45 for movement within the A-frame and pivoted adjacent the bottom of the members H⁴ is a bag holding cradle I. This cradle is provided with an adjustable bottom I' whereby adjustment may be made for varying 50 sizes of bags or packages. At the top of the cradle I is mounted a hook I² which is adapted to engage with a hook I³ mounted upon the chest B'. The hook member I² is provided with a stop I⁴ and an adjusting screw I⁵. Mounted at the bottom of the multiple hopper B is a laterally extending arm I⁶ to which is pivoted a lever I⁷ which carries a handle I⁸. The lever I⁷ adjacent the handle I⁸ is connected to the hook I² by 55 means of the link I⁹.

60 Mounted between the end members A, A and beneath the hopper and chest are a plurality of weighing mechanisms, one for each of the A-frames, whereby each bag or package is separately weighed as it is filled. A

description of one of these mechanisms will serve as a description of all. The scale beam is in reality a substantially rectangular frame including a pair of side members J joined together at the outer end J' and pivoted at the points J². The A-frame H is supported at the end J³ of the scale bar, as described above. The scale beam is provided at the end J' with an adjusting and limiting screw J⁴ which limits the downward excursion of that end of the bar. Mounted centrally of the weighing frame is a weight holding bar J⁵ upon which a main weight J⁶ is mounted. Mounted above one of the side members J is a rod J⁷ upon which an adjusting weight J⁸ is movably mounted. The main weight J⁶ is set for a given weight of package and the weight J⁸ is moved in order to make and keep the adjustment correct. 75

80 The use and operation of my invention are as follows:

The machine as shown is intended to fill three bags or packages simultaneously. In the specification only one bag filling arrangement has been described as the others 90 are identical with it. The bags are put in position within the bag holding cradle and the discharge nozzle is introduced into an opening of the bag, which is preferably of the valve type. When the bag is positioned 95 and the valve of the discharge nozzle opened, material is discharged from the hopper through the chest into the bag by means of the impellers. As the bag fills, the scale beam is gradually depressed by 100 reason of the increasing weight of the material coming into the bag. As the lowering of the bag continues the valve in the discharge spout is automatically gradually closed by a mechanism which forms no part 105 of the present invention. When the bag has been filled to the predetermined weight, the cradle will have been depressed to the bottom of its excursion and the discharge valve closed. The handle which controls the 110 cradle is then used and the cradle is tipped and the bag thrown off. The jiggling mechanism operates during the filling to jig and vibrate the bag so as to insure packing 115 of the material. The handle which controls the cradle by means of which the bag is discharged is pivotal and independent of the cradle, so that the weight of the operator's hand as he holds the handle in preparation for discharging the bag does not come 120 upon the scale and does not therefore affect the balance of the same nor the discharge of the material. 125

Although I have shown an operative device, it will be obvious that many changes in size, shape and relation of parts might be made without departing materially from the spirit of my invention and I wish therefore that my showing be taken as in a sense 130 diagrammatic.

Claims:

1. In a bag filling machine, apparatus adapted to suspend and fill a bag, a substantially horizontal rod, means to reciprocate the rod, a jiggling foot attached to one end of the rod in position to contact a bag in filling position, and a rocker bar mounted upon a fixed pivot beneath the jigger foot and pivoted at its upper end to the jigger foot at a point above the bag contacting surface of the foot.
2. In a bag filling machine, apparatus adapted to fill material into the upper end of a bag, a weighing device beneath said apparatus and adapted to weigh a bag while 15 it is being filled, a horizontal rod extending between said apparatus and said device, means to reciprocate the rod, a jiggling foot attached to one end of the rod in position to contact a bag in filling position, and a 20 rocker bar pivotally mounted upon the base of the weighing device and pivoted at its upper end to the jigger foot at a point above the bag contacting surface of the foot.

Signed at Chicago, county of Cook and 25 State of Illinois, this 24th day of May 1922.

ADELMER M. BATES.
